UNITED STATES PATENT OFFICE

HENNING W. PRENTIS, JR., OF LANCASTER, PENNSYLVANIA, ASSIGNOR TO ARMSTRONG CORK COMPANY, OF LANCASTER, PENNSYLVANIA, A CORPORATION OF PENNSYLVANIA

SURFACE COVERING AND PROCESS OF ORNAMENTING THE SAME

Application filed July 30, 1928. Serial No. 296,196.

The present invention relates to surface coverings and the process of ornamenting the same, and more especially to the ornamentation of molded inlaid linoleum.

In the drawings the invention is illustrated in Figs. 1 to 4 as embodied in a so-called handcraft type molded inlaid linoleum floor covering of the type disclosed in the Humphreys Reissue Patent No. 16,510; while in Fig. 5 the invention is shown as applied to a futuristic pattern.

In making molded inlaid linoleum the linoleum mix is applied in granular form through stencils upon the burlap backing. The process of making a molded inlaid linoleum usually consists in passing the burlap backing along the bed of the molded inlaid stencilling machine. As the burlap backing passes along the bed of the machine, the different colored mixes which make up the inlaid color pattern are applied each through its own stencil. These mixes consist of the granular cork, sometimes mixed with wood flour, coloring pigments, and the linseed oil binder, and are in a granular condition so that they may be sifted through the stencils.

The mix of one color is first applied through its stencil, then the mix of another color through its stencil, and so on, until the entire surface of the backing is covered with patches of granular mixes of different colors. At the lines of juncture between the patches of the different colored mixes the granular material necessarily intermingles somewhat.

The burlap backing carrying the patches of different colored mixes passes from the stencilling machine to a heated press which consolidates the granular mixes to form the completed linoleum.

Usually the linoleum is given two pressing operations by two presses, one acting after the other. The first press which consolidates the loose granular mix has its plate which contacts with the mix protected by a sheet of paraffined paper or cloth to prevent the mix from sticking to the plate. Usually the paper is mounted on a roll at one side of the press and fresh paper is fed through to protect the flat surface of the press at each operation of the press. The second press

operates upon the linoleum which has been consolidated by the first press and it is not necessary to apply the protecting paraffined paper or cloth over the surface of the second press, so that indenting ribs may be formed on the plate of the second press in order to ornament the linoleum as hereinafter described.

The granular mixes as they come to the consolidating press lie in patches of loose material somewhat resembling coarse damp sand. The granules therefore at the border lines between the patches inevitably become somewhat intermingled or mixed. Therefore, when the granular material is consolidated by the press, the lines of juncture between the different inlays are irregular, which is one of the characteristics of molded inlaid linoleum, as contrasted with straight line inlaid linoleum in which the lines of juncture are sharp and distinct. In the manufacture of straight line inlaid linoleum the inlays are made by cutting out pieces from previously calendered sheets of the consolidated linoleum mix and these cut-out pieces are assembled upon a burlap backing and pressed into contact with the burlap backing and into firm marginal engagement with each other by a pressing operation. The result is that the sharp straight lines of the cut-out pieces are preserved in the finished linoleum.

The irregular line of juncture between the differently colored inlays of molded inlaid linoleum has for many years been regarded as a defect and as detracting from the ornamental appearance of the moulded inlaid goods. This has been particularly objectionable in tile pattern linoleums where the block-like inlays corresponding to the tiles are contiguous, that is, where they are placed side by side and without separation by narrow inlays or "interliners" to correspond to mortar joints between the tiles.

Because of such irregular line the surface gives the impression of a rather carelessly painted-on surface coating, and does not give the impression of clearly distinct built-in inlays which is created by a straight line inlaid

linoleum with the sharp distinct lines between its tile-like inlays.

Referring for example to Humphreys re-issue patent, Reissue No. 16,510, re-issued December 28, 1926, the linoleums embodying the Humphreys invention are often made by the molded inlaid linoleum process and may be made either with or without mortar joint interliners between the tile-like blocks or inlays. When no mortar joint interliners are used, the inlays which form the blocks of the tile pattern appear to merge into each other because of the irregular juncture line, thus destroying the impression of distinctly separated and in-built differently colored inlays.

This condition may be remedied by the use of narrow interliners simulating mortar joints between the main block portions of the tile pattern, and bodily depressing such narrow interliners. In a tile pattern, these interliners are usually of a color to correspond to a mortar joint material and are bodily depressed between the blocks which correspond to the tiles. In this way, the objection to the irregular juncture line between the inlays has been overcome, both because of the depressing of the interliners and also because the irregular lines which run along both sides of the interliners give the general impression to the eye of the irregular lines which naturally occur between the edges of a tile and a hand troweled mortar joint between the tile.

However, the application of the narrow interliners between the inlays has necessitated the use of a special stencil to apply the interliners in the stenciling machine. Because of the space in the stenciling machine, the number of stenciling plates is necessarily limited, and the use of one of the stencils to lay in the interliners reduces the number of stencils which would otherwise be available for the main block portions of the pattern. In producing a pattern the problem is usually to produce it with as many shades or differences of color in pleasing contrast as possible. In order to obtain the best color values with a limited number of stencils, it is desirable that the space of a whole stencil should not be utilized merely in producing the very small area of the pattern constituted by narrow interliners.

Therefore for many patterns it is desirable that all of the stencils should be available so as to lay in the maximum number of differing colors for the main inlays. Thus in a tile pattern of the type described in the Humphreys re-issue patent, Reissue No. 16,510, it is desirable to employ all of the stencils so as to get the maximum number of different shades in the block-like tile inlays so as to simulate as wide a variety of shading as possible and to give the impression of the hit-or-miss hand laid tiles.

Where one of the stencils has to be taken

for laying in the narrow interliners, the number of different colors or shades available for the main block-like portion of the design is reduced. On the other hand, if all of the stencils are devoted to producing the block-like tile inlays, the tile-like blocks must necessarily be contiguous and separated from each other only by the irregular line of color juncture between them which, as above pointed out, has been found to be particularly objectionable in appearance. I have found that the objection existing against the irregular line between the inlays, such, for example, as between the blocks in a tile pattern linoleum without interliners, may be overcome and at the same time a greatly improved ornamental effect given to the surface of the linoleum, by depressing the irregular lines together with the marginal portion of at least one and preferably both of the contiguous inlays. As contrasted with the case in which an entire inlay is bodily depressed, as in the case of a depressed mortar joint interliner, I do not depress the entire inlays but only a narrow marginal portion or portions of the inlays along the irregular line of juncture.

In the drawings,

Figure 1 is a plan view of a piece of molded inlaid linoleum embodying my invention;

Figure 2 is an enlarged section through the linoleum of Figure 1;

Figure 3 is a plan view of another piece of linoleum showing a modification;

Figure 4 is a section through the linoleum shown in Fig. 3; and

Figure 5 is a plan view showing another piece of linoleum embodying still another modification.

Referring first to the embodiment of the invention illustrated in Figures 1 and 2 of the drawings:—Reference numeral 1 indicates generally a piece of molded inlaid linoleum. The linoleum is first made in the usual way by applying the granular linoleum mixes to the burlap backing so as to form the inlays of differing or varying colors, indicated by reference numerals 3 to 18, inclusive. By the term differing colors or varying colors I mean either different colors or different shades of the same color. Usually in making a tile pattern linoleum such as that shown in Figure 1, say with a red tile effect, the inlays are made of mixes of rather slightly different shades of red so as to give the color contrast corresponding to the different shades of red color given in burning tile in a kiln. Preferably the inlays of the different colors are arranged with the irregularity of occurrence and simulating haphazard appearance as shown in the Humphreys reissue patent, Reissue No. 16,510. The irregular lines of color juncture between the inlays which are a characteristic of the molded inlaid process are indicated by the reference numerals 19.

As shown in the drawings, no mortar joint

interliners are employed, thus leaving available all of the stencils so as to give the maximum number of varying colors for the tile-like inlays. The tile-like blocks or inlays are therefore contiguous to each other and are separated only by the irregular lines of juncture which are characteristic of molded inlaid linoleum. Because of the immediate contiguity of the tile inlays and the irregular lines between the tiles, a pattern of this type is not well adapted to molded inlaid linoleum having the usual smooth flat surface. This type of pattern has heretofore been usually made in the straight line inlays in which the appearance of the separate tiles or blocks fitted nicely against each other can be better produced, as contrasted with the blurring or "bleeding" together of the edges of the blocks in a molded inlaid linoleum. I have found however that patterns of this type may be advantageously made by the molded inlaying process with an artistic effect comparable with, although differing from, that produced by the straight line inlaying process, by depressing the irregular lines together with very narrow contiguous portions of the block-like inlays.

In carrying out my process the molded inlaid linoleum is usually first made into a sheet having the flat smooth surface as given to it by the usual first press which follows the stenciling machine. This press has a smooth flat face which can be protected against the sticking to it of the granular mixes by means of a protecting sheet of paraffined paper or cloth.

After the linoleum is thus made into a smooth sheet it then passes to the second press. The press plate of the second press is provided with narrow ribs which impress into the linoleum the narrow shallow grooves indicated by reference numerals 20 in the drawings. The linoleum at this stage has been compressed by the first press so that a ribbed press without a protecting layer of paper or cloth may be employed. Because of the ribs, it would not be practicable to employ the usual protecting sheet of paraffined paper beneath this press, as the ribs would rupture the paper.

The grooves 20 are shallow and of smooth contour so as not to catch and retain dirt. The grooves are usually about 1/32 to 3/64 of an inch deep. They are also relatively narrow compared with the width of the block-like inlays 3 to 18 both because the ornamental effect is best carried out by depressing narrow strips along the marginal edges of the inlays and also because when narrow portions only are depressed the linoleum sheet is not subjected to objectionable stretching or distortion.

As shown in Figures 1 and 2 the irregular lines preferably lie along the bottoms of the grooves 20, so that they are bordered on

each side by narrow depressed marginal edges of the adjacent inlays. It will be noted that by far the greater part of each inlay is undepressed and only the narrow strips along the marginal edges are sunk below the general surface of the inlays.

The indenting of the surface of the linoleum as herein shown produces a number of effects upon the ornamental appearance of the linoleum surface.

The irregular line of juncture which was objectionable upon a flat surface of linoleum and which would give the impression to the eye that the materials of the different tiles were intermingled into each other is overcome. The irregular line is depressed into a subordinate appearance where it is far less noticeable than it would be upon a flat surface.

The sinking of the marginal edges of the inlays into the grooves gives a color variation illusion to the eye. The surface of the groove is on a lower plane than that of the main portions of the inlays and the sides of the groove are inclined or curved. The light flowing into the grooves therefore produces an effect of high light and shade and particularly in looking at the linoleum toward a strong light, such as a window. The color in the grooves lies in shadows which are surrounded by the high lights afforded by the edges where the grooves merge into the raised portions of the inlays.

The indenting operation tends to make the linoleum material at the grooves flow sideways and raises the surface just beyond the edges of the grooves very slightly above the main body or unaffected portions of the inlays, thus still further accentuating the high lights along the edges of the grooves.

The pressure afforded by the indenting ribs upon the already consolidated sheet of linoleum has a tendency to somewhat modify the surface texture of the linoleum, thus tending to give it the appearance of a somewhat different color. Also when the linoleum is waxed or lacquered, the coating thus applied will usually be of slightly different thickness in the grooves than on the main bodies of the inlays, still further accentuating the appearance of difference in color shading.

As shown particularly in Figs. 1 and 2, the color in one of the grooves is composed of two narrow strips side by side which blend together along the irregular line of color juncture. Because of the depression and blending of these two narrow strips of color in the groove, they tend to give to the eye the impression of a color composed of the blending of the two colors, and this blended color is different from the colors of the inlays on each side of the groove.

Referring again to Figure 1, let us assume for example that the various tile inlays

are of different shades of red to simulate the different shades obtained on burning red ceramic tile, assuming, for example, that the cross-hatching of inlay 16 indicates a light shade of red, that of inlays 13 and 14 a somewhat darker red, that of inlays 4 and 8 a still darker shade of red and that of inlays 9, 12 and 17 a still darker shade of red.

The irregular line 19 is, of course, formed by the line of demarcation between the colors on each side of it. The stronger the color contrast across the sides of a portion of the line 19, the stronger will be the appearance of the line itself. Therefore, the line will tend to stand out more strongly, say, between inlays 16 and 17 where the color contrast is greatest than it will, say, between inlays 8 and 9 where there is less color contrast between the inlays. On a flat surface linoleum this difference in color contrast along one of the irregular lines 19 as the line passes between inlays having different color contrast will tend to make the line appear as if it had abrupt changes in appearance or break at the corner of the inlays. However, because of the fact that the irregular line is put into a subordinate position along the bottom of the groove and further because when there are two colors in the groove along the two sides of the line, the colors will tend to blend into a tone about half way between them, the irregular line will not have the same abrupt appearance of change as it would on a flat surface.

In order to prevent the appearance of abrupt changes in color contrast along the lengths of the grooves and in order to secure a better blending of the narrow depressed strips of color in the groove, it is preferred to make the inlays of harmonizing colors or harmonizing shades of the same color so that they may merge into a harmonious neutral appearance to the eye along the grooves.

Because of the optical illusion of the appearance of color shading and blending in the grooves, the grooves will appear to the casual glance of the eye particularly when looking toward a strong light, to be of somewhat different color than that of an undepressed inlaid portion along the sides of the grooves, and an optical impression is created of differently shaded interliners between the inlays, thus attaining somewhat the effect of interliners but without devoting a special stencil to the production of the interliners.

It is found that by doing away with the interliners and utilizing all of the stencils for laying in the main block-like portions of the pattern, and by depressing the irregular lines together with a narrow strip or strips of color formed by the depressed margins or edges of the adjacent inlay or inlays, that an artistic effect is produced which is different from that produced, on the one hand by employing the same color pattern without

indentation, and on the other hand from employing interliners which are bodily depressed between the main blocks of color.

In Figure 3 is illustrated a modification in which the irregular lines 19-a which form the boundaries between the differently colored inlays instead of being located along the bottom groove 20-a, run along an edge of the groove. In this case the marginal portion of but one of the inlays which is contiguous to the line is depressed.

The line itself is located near or upon the slope at the side of the groove. While it is preferred to run the irregular line along the bottom of the groove as shown in Figures 1 and 2, the arrangement shown in Figures 3 and 4 may be employed since it is found to minimize the objectionable appearance of the line and also since it gives the illusion of color shading between the depressed marginal portion of the inlays and the raised or main portion thereof. As before mentioned, this feeling of color contrast or illusion to the eye is usually heightened when the linoleum is waxed or lacquered.

In Figure 5 is shown another modified embodiment of the invention. The design in this case is a so-called modernistic or futuristic design. Certain of the inlays indicated by reference numerals 30 and 31 are surrounded by depressions or grooves 20-b which contain the irregular color lines 19-b and the narrow bands formed by the depressed marginal portions of the adjacent inlays.

In Figure 5 only a part of the irregular lines of color juncture between inlays are depressed, namely, the irregular lines of color juncture surrounding the inlays 30 and 31, leaving the lines of color juncture between other inlays standing in emphasized and prominent position upon the flat surface of the linoleum. This produces a highly distinctive and contrasting type of linoleum pattern.

In all of the figures of the drawings, the various cross-hatching and shade lines are employed on the inlays to indicate different colors or shades of color.

While the invention is illustrated in Figures 1 to 4 as being applied to a handcraft tile pattern linoleum without interliners, the invention may be embodied otherwise as shown for example, in Figure 5, in other types of linoleum design. The invention is therefore not limited to its preferred embodiment, but may be otherwise embodied and practiced within the scope of the following claims.

I claim:

1. The method of decorating a surface which comprises forming on such surface immediately adjacent areas of differing colors having irregular lines of color juncture between them, and impressing in the surface narrow shallow grooves which include irregu-

lar juncture lines and marginal portions only of the contiguous color areas.

2. As a new article of manufacture a decorative surface comprising contacting areas of differing colors having irregular lines of color juncture between them, and narrow shallow grooves impressed in the surface along such juncture lines and including in the depressed area the irregular juncture line together with the marginal portions only of the contiguous color areas.

3. The method of decorating the surface of a linoleum having contacting molded inlays of varying colors and the irregular lines of color juncture between them characteristic of molded inlaid linoleum, which comprises impressing in the linoleum surface narrow shallow grooves along the irregular lines of color juncture between inlays and thereby depressing such irregular lines into subordinate positions together with a narrow marginal portion only of at least one of the contiguous inlays.

4. As a new article of manufacture, a molded inlaid linoleum comprising contacting inlays of varying colors separated by the irregular lines of color juncture characteristic of molded inlaid linoleum, and having the irregular juncture lines together with narrow marginal portions of the inlays on both sides of the lines depressed below the main bodies of the inlays.

5. As a new article of manufacture, a molded inlaid linoleum comprising contacting inlays of varying colors separated by the irregular lines of color juncture characteristic of molded inlaid linoleum, and having some at least of the irregular color juncture lines together with a narrow marginal portion only of the contiguous inlays sunk below the general surface level of such inlay.

6. As a new article of manufacture, a tile pattern molded inlaid linoleum consisting of tile-like inlays of varying colors contacting with each other and having the irregular lines of color juncture characteristic of molded inlaid linoleum, and relatively narrow shallow grooves formed in the surface of the linoleum between said tile-like inlays and following the irregular lines of juncture.

7. As a new article of manufacture, a molded inlaid linoleum having contacting inlays of varying colors and having the irregular lines of color juncture characteristic of molded inlaid linoleum, and narrow shallow grooves between inlays containing the irregular line and the depressed marginal portions of the contiguous inlays on both sides of the line, the greater part of such inlays being undepressed.

8. As a new article of manufacture, a tile pattern molded inlaid linoleum consisting of tile-like inlays of varying and harmonizing shades of color contacting with each other and having the irregular lines of juncture

characteristic of molded inlaid linoleum, and having relatively narrow shallow grooves formed in the surface of the linoleum between said tile-like inlays and containing the irregular juncture lines and depressed marginal portions of the inlays.

9. As a new article of manufacture, a tile pattern molded inlaid linoleum consisting of tile-like inlays of varying colors abutting with one another and without interliners, there being the irregular line of juncture characteristic of molded inlaid linoleum, and relatively narrow shallow grooves formed in the surface of the linoleum between said tile-like inlays and following the irregular lines of juncture.

10. As a new article of manufacture, molded inlaid linoleum comprising inlays of varying colors contacting on the irregular lines of juncture characteristic of molded inlaid linoleum, the linoleum having grooves along the lines of juncture, the marginal portion of at least one of the inlays being depressed to form the groove, said depressed marginal portion being at least substantially half the width of the groove.

In testimony whereof I have hereunto set my hand.

HENNING W. PRENTIS, JR.
